UNITED STATES PATENT OFFICE.

ERNST SIMON, OF CHICAGO, ILLINOIS.

WAGON-COVER.

SPECIFICATION forming part of Letters Patent No. 487,544, dated December 6, 1892.

Application filed February 19, 1892. Serial No. 422,147. (No model.)

To all whom it may concern:

Be it known that I, ERNST SIMON, residing at Chicago, Cook county, Illinois, have invented a certain new and useful Improvement 5 in Wagon-Covers, of which the following is a specification.

My invention relates to covers which are used to protect drivers of wagons and other vehicles from rain, sun, snow, &c.; and its object is to provide means whereby this cover and its supporting-framework can be readily brought into position for use when desired and as readily stowed away when it is desired not to use the same.

15 My invention consists in the features, details of construction, and combinations hereinafter described and claimed.

In the drawings, Figure 1 is a perspective view of the adjustable framework forming a 20 part of my invention, the cover being applied thereto and indicated in dotted lines; Fig. 2, a detail view illustrating the method of fastening the framework when in position for use; Fig. 3, a perspective view of the cover 25 removed from the framework; and Fig. 4, a side elevation of the box or seat, the foot-board, and a portion of the body of the wagon.

In constructing my invention I first make a telescopic or adjustable framework. The vertical portion of this framework is made in any 30 desired number of parts, adapted to be readily expanded or contracted when desired. In the drawings I have shown each portion of this framework as made in three parts, as follows: Secured to the side of the wagon-box A are tubes B, there being preferably two of these at each side of the wagon-box. These are secured to the wagon in any suitable manner, as by means of sockets b and 35 straps b'. In these tubes slide tubes C and in these tubes C slide rods D. The relative dimensions of these tubes and rods may be varied in accordance with the size of the wagon to which they are to be applied or the 40 pleasure of the person constructing them. To hold these parts in an extended position, I provide catches E. One of these catches is more particularly shown in Fig. 2. They are pivoted, as shown, to the tubes B, adapted to pass 45 through openings in these tubes, and engage with notches or depressions in the tubes C in

order to hold these tubes in any position. Similar catches are provided adapted to engage with the rods D to hold or lock them.

Extending across the top of the framework 55 at each side of the seat from one rod D to the other are tubes F, secured to the rods by means of T's f' or in any other suitable manner, and in these tubes are slide-rods G, the tubes being provided with catches E, similar 60 to those already described.

In Fig. 4 the cover is removed and the parts of the framework folded together in the position which they occupy when not in use, and in Fig. 1 I have shown them as extended in a 65 position for use. I then make out of canvas or other suitable material a cover H of any desired dimensions and preferably in the form shown in Fig. 3, wherein it is provided with a top, back, and sides, being open at the front. 70 Along the front and back edges of the top of this cover are rods II', having pins i' at their ends. When the cover is applied, the pins i engage with holes in the T's f and the pins i' with holes in the ends of the rods G, the cover 75 being firmly held by this means.

When it is desired to use the device, the framework is extended into the position shown in Fig. 1 and cover passed over it and the pins inserted into their respective holes, 80 this position of the cover being indicated by dotted lines in Fig. 1. When it is desired to remove the cover, the canvas is taken off and the framework folded up in the position shown in Fig. 4. By this means I provide a simple 85 and economical wagon-cover, which is adapted to be readily changed from a position of non-use into one for use, and vice versa, which affords full protection when in use, and which occupies little, if any, room when not in use. 90

While I have described more or less precise forms, I do not intend to be limited unnecessarily thereto, but contemplate changes in form, proportions, and the substitution of equivalents, as may necessary or desirable. 95 For example, the number of the telescopic rods or tubes may be changed, as desirable, to adapt the device to wagons of different sizes, the canvas hood may be secured to the framework by other means than the pins, and similar 100 changes may be made without departing from my invention, the gist of which consists in

providing a wagon-cover comprising an adjustable or extensible framework and a canvas hood adapted to be supported thereby.

It should be understood that although I have only shown this cover as applied to the seat of the vehicle it may be so made as to cover the entire body of the wagon or other vehicle, if this be desired.

I claim—

- 10 1. A wagon-cover comprising a telescopic framework capable of being extended into a position for use or shut up in position of non-use and a cover of suitable material adapted to be supported by such framework when in position for use and to be removed therefrom when in position of non-use, the framework when collapsed being entirely out of the way, substantially as described.
- 15 2. A wagon-cover comprising a telescopic framework, each member whereof is made in at least two sections, one fitting within the other, whereby the framework may be ex-

tended into a position for use or collapsed into a position of non-use, in which latter position it is entirely out of the way, substantially as described.

3. A wagon-cover comprising a framework which is collapsible and extensible both vertically and horizontally and a cover of suitable material supported thereby, substantially as described.

4. A wagon-cover comprising a telescopic framework capable of vertical and horizontal adjustment to different positions, whereby it can be folded up into a position of non-use or extended into a position for use, means for holding the parts of such framework in an extended position, and a cover of suitable material engaging with and supported by such framework, substantially as described.

ERNST SIMON.
